Primary Examiner — Vy N Koenig(74) *Attorney, Agent, or Firm* — Cooper Legal Group, LLC(57) **CLAIM**

The ornamental design for a perfume vaporizer, as shown and described.

DESCRIPTION

FIG. 1 is a front, top, right perspective view of a perfume vaporizer showing our new design;

FIG. 2 is a front, top, right perspective view thereof in alternate usage configuration;

FIG. 3 is a front view of the perfume vaporizer of FIG. 1;

FIG. 4 is a back view thereof;

FIG. 5 is a left view thereof;

FIG. 6 is a right view thereof;

FIG. 7 is an enlarged top view thereof; and,

FIG. 8 is an enlarged bottom view thereof.

The broken lines shown in the figures depict portions of the perfume vaporizer that do not form part of the claimed design.
